US0D1104403S

(12) **United States Design Patent** (10) **Patent No.:** **US D1,104,403 S**
(45) **Date of Patent:** **** Dec. 2, 2025**

(54) **PORTABLE SAFE**

(71) Applicant: **Jinhua Xinlei Lock Industry Co., Ltd., Zhejiang (CN)**

(72) Inventor: **Wanqiang Shang, Hebei (CN)**

(73) Assignee: **Jinhua Xinlei Lock Industry Co., Ltd., Zhejiang (CN)**

(**) Term: **15 Years**

(21) Appl. No.: **29/967,774**

(22) Filed: **Oct. 12, 2024**

(51) LOC (15) Cl. **99-00**

(52) U.S. Cl.

USPC **D99/28**

CLAIM

The ornamental design for a portable safe as shown and described.

DESCRIPTION

FIG. 1 is a front, bottom, and left perspective view of a portable safe showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, top, and right perspective view thereof.

The broken lines shown in the drawings represent portions of the portable safe that form no part of the claimed design.

1 Claim, 8 Drawing Sheets
